UNITED STATES PATENT OFFICE.

GEORGE D. SCHEIFFLER, OF JACKSON, MICHIGAN, ASSIGNOR TO HOLTON & WEATHERWAX CO., LTD., OF JACKSON, MICHIGAN.

MORTAR-MIXER.

No. 922,724.

Specification of Letters Patent.

Patented May 25, 1909.

Application filed October 2, 1907. Serial No. 395,511.

To all whom it may concern:

Be it known that I, GEORGE D. SCHEIFFLER, a citizen of the United States of America, residing at Jackson, in the county 5 of Jackson and State of Michigan, have invented certain new and useful Improvements in Mortar-Mixers; and I do hereby declare the following to be a full, clear, and exact description of the invention, such as will enable 10 others skilled in the art to which it appertains to make and use the same.

My invention relates to improvements in mortar mixers, and more particularly to devices for mixing concrete having therein 15 gravel, small stones, or other like solid substances. In mixing such material this gravel or small stones will be liable to clog or break the machine and will be frequently jammed between the blades of the mixer and the 20 trough of the same to the injury or stoppage of the machine.

The object of my invention is to provide a machine that will mix material for forming concrete having gravel, stones or other 25 small solid material therein and that will not be clogged or injured thereby; and a further object of my invention is to provide means for preventing the adhesion of the material to the trough in which it is mixed. I 30 accomplish these results by providing the rotating shaft in the axis of the trough with flexible, flat strips radially disposed thereon, and of such length as to engage and traverse the interior of the trough, whereby the strips 35 will yield to any obstruction that may get between them and the trough, such as a small stone and pass over the same, without injury or stoppage, and which will also constantly clear the trough from any adhering 40 material by scraping the inner surface thereof and that will not readily become worn away and fail to contact the trough.

A further object is to provide a device that may be easily and quickly repaired whenever necessary, and to provide the same with various new and useful features, herein-after more fully described and particularly pointed out in the claims, reference being had to the accompanying drawings, in 50 which:

Figure 1 is a side elevation of a device embodying my invention with a part of the trough or case broken away; Fig. 2 an enlarged plan view of a portion of the same 55 with the rotating parts in horizontal section;

Fig. 3 a detail of the said parts in end elevation; Fig. 4 a further enlarged detail of the sleeve and portions of the flexible strips; Fig. 5 a detail showing the inner surface of the sleeve; and Fig. 6 a detail in longitudinal section showing the manner of retaining the flexible strips in the sleeve.

Like numbers refer to like parts in all of the figures.

1 represents a portion of the feed regulator for supplying material to the mixer; 65 2 the mixer trough having a concave inner surface concentric with the axis of the shaft; 3 the rotative shaft in the axis of the trough; 4 a sleeve surrounding the shaft and divided 70 longitudinally into two equal parts and secured to the shaft by transverse bolts 6.

Inserted in any number of series of spirally arranged holes in this sleeve (two being shown) are numerous radially projecting, 75 flexible, flat strips 5 preferably of spring steel. These strips are bent in U-shape at the middle and the middle portions span the spaces between two adjacent holes in the sleeve, and the respective ends of the strips 80 extend radially outward through these holes. When the sleeve is bolted to the shaft, these strips are securely held in the sleeve and extending radially outward contact and traverse the inner surface of the trough 2 at 85 their ends. Being flexible they will yield and bend backward and thus maintain intimate scraping contact with the trough and constantly remove from the same any adhering material. By the spiral arrangement of 90 these strips they also serve as a conveyer to move the material longitudinally of the trough and being inserted in the openings with their edges presented transversely to the direction of the spiral, they engage the material edgewise and are thus sufficiently rigid 95 to move the same along in the trough.

In the event that the gravel or small stones used in the concrete should get between the trough and the ends of these strips, the latter 100 being flexible, will yield and pass over the same, and thus avoid any clogging or breaking of the machine. I thus provide a device that will successfully and satisfactorily mix concrete having gravel or stones therein, and 105 will also keep the trough entirely clear from any adhering material. When these flexible strips eventually become worn so that they are no longer useful, the sleeve can be easily and quickly detached by removing the bolts 110

6 and new strips 5 inserted as occasion requires.

What I claim is:

1. In a concrete mixer, the combination 5 of a concave trough, a rotative shaft mounted therein, a longitudinally divided sleeve attached to the shaft and having a series of openings, and a series of flat flexible and superposed strips bent at the middle and inserted in two adjacent openings in the sleeve and having their flat surfaces arranged spirally to the shaft to move the material longitudinally of the trough.
- 10 2. In a concrete mixer, the combination 15 of a concave trough, a rotative shaft mount-

ed therein, a longitudinally divided sleeve detachably secured to the shaft and having one or more spirally arranged rows of holes, and flat flexible strips bent at the middle and inserted in two adjacent holes and with 20 their ends engaging the trough, and their width arranged transverse to the direction of the spiral of the rows of holes.

In testimony whereof I affix my signature in presence of two witnesses.

GEORGE D. SCHEIFFLER.
